UNITED STATES PATENT OFFICE.

MONROE KOHN AND GEORGE J. REITER, OF CHICAGO, ILLINOIS, ASSIGNEES TO F. LEWALD & COMPANY, OF CHICAGO, ILLINOIS, A CORPORATION OF ILLINOIS.

GARMENT-HANGER.

1,205,644.

Specification of Letters Patent.

Patented Nov. 21, 1916.

Application filed September 26, 1913. Serial No. 791,886.

To all whom it may concern:

Be it known that we, MONROE KOHN and GEORGE J. REITER, citizens of the United States, residing at Chicago, county of Cook, 5 State of Illinois, have invented a certain new and useful Improvement in Garment-Hangers, and declare the following to be a full, clear, and exact description of the same, such as will enable others skilled in 10 the art to which it pertains to make and use the same, reference being had to the accompanying drawings, which form a part of this specification.

Our invention has for its object to produce a simple and novel garment hanger which will cause the fabric of a coat between the shoulders and around the neck to lie smooth and flat.

A further object of our invention is to 20 produce a simple and compact coat hanger upon which trousers or skirts may be supported without interfering with the coat arranged on the hanger.

The various features of novelty whereby 25 our invention is characterized will herein-after be pointed out with particularity in the claims; but, for a full understanding of our invention and of its objects and advantages, reference may be had to the following 30 detailed description taken in connection with the accompanying drawing, wherein:

Figure 1 is a front view of a hanger arranged in accordance with our invention; Fig. 2 is a view looking toward the left in 35 Fig. 1; Fig. 3 is a view similar to Fig. 1 showing a modified form of hanger; and Fig. 4 is a top plan view of the hanger shown in Fig. 3.

Referring to Figs. 1 and 2 of the drawing, 1, 2 and 3 represent the three sides of a frame made in the form of an isosceles triangle at the apex of which is a hook, 4, or other suspending device. The frame may 40 conveniently be made of a single piece of wire. After the frame is formed, the portions of the sides 2 and 3 adjacent to the apex are bent forward so as to bring the upper half of the triangular frame in a plane making an obtuse angle with the plane of the lower half.

When the hanger is placed in a coat it is arranged so that the inclined upper portion extends toward the front, thus allowing it to engage the rear portion of the collar 45 while the side or end portions underlie the

shoulder portions, and allowing the fabric to set naturally. The lower member, 1, of the frame serves as a bar on which trousers may be hung.

If desired, the members 2 and 3 of the 60 frame may be bent at points between their ends so as to provide forwardly projecting hooks, 5 and 6, respectively, upon which a skirt may be hung.

The hanger illustrated in Figs. 3 and 4 65 of the drawing is the same in principle as the other hanger although differing therefrom slightly in structural details. The second form of hanger may also conveniently be made of one piece of wire the ends 70 of the horizontal piece or cross bar, 7, being bent upwardly as indicated at 8 and 9 and then being bent so as to form with the lower portions of the other two frame members 10 and 11, loops or rings, 12 and 13, which 75 give a wide bearing for each of the shoulders of a garment. The upper portions of the members 10 and 11 are bent forwardly in the same way as the upper portions of the members 2 and 3.

While we have illustrated and described 80 with particularity only a single preferred form of our invention, we do not desire to be limited to the exact structural details thus illustrated and described, but intend 85 to cover all forms and arrangements which fall within the definitions of our invention constituting the appended claims.

We claim:

1. A garment hanger comprising an open 90 wire frame having the shape of an isosceles triangle, approximately the upper half of the frame being bent forwardly so as to make a considerable angle with the remainder and bring the apex a considerable distance in advance of the other two corners of the triangle.

2. A garment hanger comprising an open 100 wire frame having the shape of an isosceles triangle, approximately the upper half of the frame being bent forwardly so as to make a considerable angle with the remainder, the two upper members of the frame being bent into depending hooks.

3. A garment hanger having the general 105 shape of an isosceles triangle, approximately the upper half of the triangle being bent forwardly so as to bring the upper and lower halves of the hanger into two planes making a considerable angle with each other 110

and bring the apex a considerable distance in advance of the other two corners.

4. A garment hanger comprising an open wire frame having the shape of an isosceles triangle, the frame being bent laterally along a line approximately halfway between the base and the apex so as to shape the hanger into two flat portions lying at an angle to each other, the two upper sides of 10 the triangle being bent into the form of

depending hooks in the vicinity of the aforesaid line.

In testimony whereof, we sign this specification in the presence of two witnesses.

MONROE KOHN.
GEORGE J. REITER.
